UNITED STATES PATENT OFFICE.

WILLIAM SHIRK, OF PANAMA, IOWA.

WRENCH.

SPECIFICATION forming part of Letters Patent No. 701,951, dated June 10, 1902.

Application filed June 10, 1901. Serial No. 64,012. (No model.)

To all whom it may concern:

Be it known that I, WILLIAM SHIRK, a citizen of the United States, residing at Panama, in the county of Shelby and State of Iowa, 5 have invented certain new and useful Improvements in Wrenches; and I do hereby declare the following to be a full, clear, and exact description of the invention, such as will enable others skilled in the art to which it applies to make and use the same.

This invention relates to wrenches of the alligator type, and aims to provide a simple, novel, and effective means for positive actuation of the jaws to adjust them to grip different sizes of nuts, rods, or other objects required to be turned by force.

For a full description of the invention and the merits thereof and also to acquire a knowledge of the details of construction of 20 the means for effecting the result reference is to be had to the following description and drawings hereto attached.

While the essential and characteristic features of the invention are necessarily susceptible of modification, still the preferred embodiment of the invention is illustrated in the accompanying drawings, in which—

Figure 1 is a plan view of a wrench embodying the invention. Fig. 2 is a view similar to Fig. 1 with the cap-plate removed. Fig. 3 is a transverse section on the line X X of Fig. 1. Fig. 4 is a central longitudinal section.

Corresponding and like parts are referred 35 to in the following description and indicated in all the views of the drawings by the same reference characters.

The stock or frame 1 is widened at one end to receive the operating parts and is contracted at the opposite end to provide a handle and has an opening extending inward from the widened end to accommodate the jaws and the adjunctive parts. Plates 2 are secured to the opposite sides of the stock or 45 frame to close the opening thereof and retain the working parts in place.

The jaws 3 are arranged lengthwise of the stock or frame and are pivoted at a point between their ends to the plates 2, the opposing or proximal edges of the inner end portions of the jaws flaring, so as to receive between them a wedge or cam 4, by means of

which the inner ends of the jaws are forced apart and their outer ends caused to approach more or less closely, so as to grip an object of given size. The inner or gripping edges of the jaws are toothed or serrated, so as to prevent slipping and enable the jaws to obtain a firm hold of the object to be turned. Flat springs 5 are secured at one end to shouldered portions of the stock or frame and have the opposite end bearing inward upon the inner end portions of the jaws 3, so as to press said ends together when withdrawing the cam or wedge 4 from therebetween. The jaws 3 60 correspond in thickness to about the thickness of the stock or frame, so as to lie in the plane thereof and prevent binding between the plates 2 when the latter are firmly clamped against the sides of the stock.

The wedge or cam 4 is provided at one end with a set-screw or threaded stem 6, located in the inner end portion of the opening formed in the stock or frame, opposite sides being plain, so as to come between the plates 2 and 70 within the plane of the sides of the frame 1. A nut 7 is provided for coöperation with the set-screw or threaded stem 6 and is arranged to operate in notches 8, formed in the walls bordering upon the opening of the stock or frame. Openings 9 are formed in the inner ends of the plates 2 for opposite portions of the nut to project through, so as to be engaged by the thumb and finger of the hand for rotation when it is required to adjust the 80 set-screw to vary the distance between the outer ends of the jaws 3. The nut is milled or otherwise roughened to facilitate its turning when desired. A pin 10 passes transversely through the wedge or cam 4, and its 90 ends enter longitudinal slots 11, formed centrally in the side plates 2, whereby the wedge is centralized and prevented from lateral displacement. The wedge or cam 4, being caused to move in a straight line and held from lateral displacement, fixes the position of the jaws 3 with reference to the stock or frame and insures their occupying a central position with reference to the stock or frame at all points of adjustment.

The stock or frame may be readily cast, stamped, or drop-forged, and the same is true of the remaining parts, and the construction is such that the elements can be readily as-

sembled and are accessible at any time for repair or other purpose.

Having thus described the invention, what is claimed as new is—

- 5 The herein-described wrench comprising a stock or frame of uniform thickness throughout its length and breadth having one end contracted and constituting a handle and having its opposite end widened and provided
10 with a slot extending inwardly and opening through opposite sides of the stock, said slot being flared at its outer end, contracted at its inner end and widened at a point intermediate the ends of the contracted part, plates
15 secured to opposite sides of the stock and closing the sides of the slot thereof and having longitudinal slots and openings in coincident relation, jaws pivoted between the plates, springs secured to the stock and exerting an

inward pressure upon the inner end of the 20 jaws, a threaded stem located in the inner contracted end of the slot formed in the stock and having a cam or wedge to enter between the inner ends of the jaws and having extensions to operate in the longitudinal slots of 25 the aforementioned plates, and a nut mounted upon the threaded stem and arranged to operate in the widened portion of the aforesaid slot of the stock and having opposite portions projecting through the openings in the 30 side plates, substantially as set forth.

In testimony whereof I affix my signature in presence of two witnesses.

WILLIAM SHIRK. [L. S.]
